UNITED STATES PATENT OFFICE.

DANIEL L. BRAINE, OF NEW YORK, N. Y., ASSIGNOR TO COMPOSITE TIE-PLATE CORPORATION, OF NEW YORK, N. Y., A CORPORATION OF NEW YORK.

RAIL-SUPPORTING DEVICE.

1,076,813.

Specification of Letters Patent.

Patented Oct. 28, 1913.

Application filed October 24, 1912. Serial No. 727,537.

To all whom it may concern:

Be it known that I, DANIEL L. BRAINE, a citizen of the United States, residing at New York, in the county of New York and State 5 of New York, have invented certain new and useful Improvements in Rail-Supporting Devices, of which the following is a specification.

This invention relates to improvements in 10 rail-supporting devices, commonly termed tie plates, and has for its object to provide an improved form of rail-supporting device which will do away with the crushing or cutting of the tie or similar support.

15 Another object of this invention is to provide a rail-supporting device which will prevent lateral movement of the rail and provide for lateral adjustment thereof.

It has been found that where excessive 20 thrust of car wheels takes place upon one rail, wearing thereof ensues, and in time the wear of the rail becomes so great as to require readjustment of the track to provide for the correct track "gage." In ordinary 25 railway track construction this involves considerable time and trouble. By the use of my improved device it is merely necessary to slightly loosen the rail spikes and rotate the main fastening means to cause the desired 30 lateral adjustment of the rail and obtain the desired gage, as will be hereinafter more fully described.

In the accompanying drawings—Figure 1 is a side elevation, showing the rail in cross 35 section. Fig. 2 is a plan view of the rail. Fig. 3 is a transverse cross section, showing the rail in one position. Fig. 4 is a view similar to Fig. 3, showing the result of wear on the rail, and also showing the entire device 40 adjusted laterally from the position shown in Fig. 3; and Fig. 5 is a perspective view, showing my device in disassembled relation.

Like numerals and letters refer to like 45 elements throughout the drawings, in which—A designates the conventional form of rail, having the usual flanged base 10 adapted to be carried upon a cushioning block or pad B, upon which is mounted a metal frame C. The usual form of railway 50 tie, sleeper, or similar support is designated by the letter D.

The metal frame is provided with top or cross members 15 and 16, respectively, spaced apart a distance equal to the width,

so as to embrace or practically fit the flanged rail base. Each of these top members is provided with spiking slots 17, opening into the space between the top members 15 and 16. Shoulders 18 and 18^a are provided at the inner side of the top portions 15 and 16, as illustrated in Fig. 5. The top members are provided with shoulders 19, dished out around the slots 17. The metal frame is further provided with side members 20, partially cut away or recessed—as indicated by the numerals 21—between the top members, so that the upper surfaces thereof in the assembled structure lie below the upper surface of the "pad" member, as shown by 60 the dotted line in Fig. 5. This metal frame is further provided with a shouldered end 22 extending downwardly from the top portion 15, and with a base flange—as I term it—24 extending or stepped outwardly from 65 said end. Ribs or braces 25 serve to rigidly connect the end 22 and the base flange. This stepped base flange is also provided with a centrally located spiking slot 26, and with a shoulder 27 extending from the inner end 70 of the slot to the end 22 of the frame. The lower surface of each side member preferably terminates short of the plane of the under surface of the base flange, as shown in Fig. 5, the base flange being adapted to 75 lie on the surface of the tie 15.

The block or pad B is adapted to be carried in the frame, and is preferably of such width as to fit closely between the sides and of such thickness as to bring its under surface in the same plane with the under surface of the base flange of the metal frame when in assembled relation, one end of said block B abutting against the inner surface of the end 22 of the metal frame. This 80 block pad is provided with elliptical spiking apertures or slots 30, adapted to rest beneath and register with the spiking slots 17 in the metal frame, and is preferably formed of hard, tough wood that is adapted 85 to receive the cutting and crushing effect of the rail.

When the device is assembled, the frame C is inserted beneath the base of the rail, and the block B is placed thereunder. The top 105 member 15 of the metal frame is located at the outer side of the rail. The distance between the top members 15 and 16 being approximately equal to the width of the flanged base rail, it will be apparent that 110

lateral movement of the rail, relative to the metal frame and block, will be prevented by the inner edges and shoulders of the top members.

5 Inasmuch as a greater thrust from the rail base generally occurs at the outer side thereof, the shoulders 18 of the top member 15, located as stated above, tend to counteract such thrust, the shoulders 18^a of the member 16 also serving to permit side movement in the opposite direction. It will be apparent that side thrust from the rail will be transmitted by said top portions, receiving such thrust, to all of the spikes through the medium of said metal frame. The cut-out portions 21 of the side members 20 of the frame are out of contact with the rail base, and the under-surfaces of the sides 20 are slightly out of contact with the upper surface of the tie or similar support. It will, therefore, be apparent that all cutting or crushing due to the contact of the metal frame on the tie, caused by the load of or on the rail, will be obviated.

20 25 After having assembled the device, the screw spikes 31, having the heads 32, are inserted through slots 17 and 30 and screwed in position, the under surfaces of the heads being adapted to rest in the dished-out portions of the shoulders 19 around the slots 17 and being supported thereby slightly out of contact with the rail base. The heads of the screw spikes project over and serve to prevent upward movement of the rail base in the usual manner.

30 35 40 45 50 55 60 65 70 75 80 85 90 95 100 105 110 115 120 125 130 When the track is first laid in connection with my improved device, as illustrated in Fig. 3, an adjusting screw spike 33, having a head 34, is inserted through the spiking aperture 26 in the stepped base flange 24 which rests upon the upper surface of the tie D. This adjusting spike is provided with an eccentric shoulder 36, located below the head 34 and adapted to contact with the outer surface of the shoulder 27. In the first use or arrangement of the device the spike 33 when screwed to final position is arranged with the shoulder 36 out of contact with shoulder 27 in the position shown in Fig. 3. As the inner surface or gage side of the rail is gradually worn, as shown in Fig. 4, the correct gage of the track obviously is disturbed. To readjust the same and obtain the desired gage, it is merely necessary with my improved device, to slightly loosen the screw spikes 31 and rotate the adjusting screw spike from the position shown in Fig. 3 to that shown in Fig. 4, whereupon the eccentric shoulder 35, contacting with the shoulder 27, will operate to move the block B and frame C, together with the rail A, to desired position and firmly hold it in such position, whereupon the screw spikes 31 may be again tightened.

65 It is believed that the operation of my

device is sufficiently clear from the above to enable those skilled in the art to practice the invention. While, therefore, I have shown and described my invention with more or less particularity, I do not wish to be restricted thereto beyond the scope of the appended claims.

What I claim is:

1. In a device of the class described, a rail supporting pad, a metal frame member adapted to rest on said pad, said frame comprising depending sides contacting with the sides of said pad and a top portion extending between said sides and resting on said pad, said top portions being spaced apart to fit the pads of a rail, means to adjustably secure said frame and pad to a supporting tie, and means to laterally adjust said frame and pad with respect to said tie. 70

2. In a device of the class described, a rail supporting pad member, a metal frame member, and means to secure said frame and rail-supporting member to a tie, said means being adapted to be operated to laterally adjust said metal frame and rail-supporting member. 85

3. In a device of the class described, a metal frame, said frame being provided with spaced apart top members, each of said top portions being provided with spiking slots, 95 whereby said frame is capable of lateral movement relative to spikes inserted therethrough.

4. In a device of the class described, a metal frame, said frame being provided with spaced apart top members to closely fit the flanged base of a railway rail, each of said top members being provided with spiking slots, each of said top members being provided with a shoulder adjacent its inner edge. 100

5. In a device of the class described, a metal frame provided with spaced apart top members to closely fit the flanged base of a railway rail, and a stepped base flange extending downwardly and outwardly from said metal frame at one end thereof and having a spiking slot. 110

6. In a device of the class described, a metal frame provided with spaced apart top members to closely fit the flanged base of a railway rail, a stepped base flange extending downwardly and outwardly from said frame at the end thereof and provided with a spiking slot, and a shoulder partially surrounding said last named slot. 115

7. In combination, a metal frame having spaced apart top members to embrace or closely fit the flanged base of a railway rail, a stepped base flange extending downwardly and outwardly from one end thereof, the lower flange of which is provided with a slot, and an adjusting screw spike in said slot to secure said frame against lateral movement and provide for desired adjustment. 125 130

20

25

30

8. In combination, a metal frame having side members and a stepped base flange extending outwardly from one end thereof and provided with a slot therein, a shoulder located adjacent said slot, and an adjusting screw spike projecting through said slot to secure said frame against lateral movement, said spike being provided with an eccentric shoulder adapted to contact with the shoulder of said frame base flange, whereby rotation of said screw spike will operate to laterally move said frame to adjust as well as retain the same in adjusted position.

9. In a device of the class described, the combination of a pad member forming the intermediate support between the rail and its sleeper, a metal frame having side members arranged out of contact with both rail and

sleeper and embracing the pad to prevent its lateral displacement, top members substantially resting in said pad and spaced apart to embrace or closely fit the flanged base of the rail, a downwardly and outwardly extending stepped base provided with a shouldered slot, an adjusting screw in said slot for adjusting the assembled structure to obtain the desired gage of track, and spikes passed through both frame and pad into the sleeper to firmly hold the assembled structure in operative position.

In testimony whereof, I have subscribed my name.

DANIEL L. BRAINE.
